UNITED STATES PATENT OFFICE.

CHARLES B. MORAN, OF SWISSVALE, PENNSYLVANIA.

METHOD AND APPARATUS FOR SEPARATING SHEETS.

Application filed March 14, 1927. Serial No. 175,834.

This invention relates to separating sheets, such as those comprising rolled packs. It has other applications such as separating annealed sheets, but is herein described as applied to packs. After a pack has been rolled, it is sheared to size and the sheets are then separated. The sheets tend to adhere because of a welding or semi-welding action which takes place between the surface of adjacent sheets and also because of the locking together of the sheet edges occasioned by the shearing operation. The customary practice is to grasp the corner of a pack and "work" it so as to separate the corners of the sheets and then take the sheets one at a time and strip them from the pack. This operation is slow, is necessarily a manual one, and, if the sheets tend to adhere tightly, is unsatisfactory. I provide a machine whereby the packs may be expeditiously separated. I flex the entire pack over successive lines of flexure, such flexure extending entirely across the pack. This is preferably done by engaging the pack between cooperating belts and moving the belts in a crooked path, preferably over flexing rolls. The belts engage the pack and cause the sheets to "slide" over one another during the flexing operation. Preferably the sheets are fed to the machine diagonally, as this is found to result in better separation.

In the accompanying drawings which illustrate the present preferred embodiment of my invention,

35 Figure 1 is a top plan view of a pack separating machine, and

Figure 2 is a vertical section taken on the line II—II of Figure 1.

In the illustrated embodiment of the invention there is shown a frame 2 supporting flexing rolls 3 and 4. Power is supplied by a belt pulley 5 on the shaft of the flexing roll 3. The shafts of the rolls 3 and 4 are connected by gears 6.

45 The machine is provided with belts which feed the packs around the flexing rolls. The pack is introduced to the machine by laying it on the top run of two sets of belts. The belts in the first set have been given the reference character 7 and those in the second set have been given the reference character 8. Considering first a belt 7, it will be seen from Figure 2 that starting at the upper run 7^a, it passes around the flexing roll 4, thence around 55 an idler 9, thence over an idler 10 to an idler 11, thence over an idler 12 to an idler 13. The

idler 13 is carried by a yoke 14 slidably mounted in cross members 15 of the frame. It is provided with a tension spring 16 having an adjustable backing member 17. In 60 this manner any desired tension may be maintained on the belt. From the idler 13 the belt passes over idlers 18 and 19 to return to the top run 7^a.

Each belt 8 passes over the flexing roll 4, 65 thence to an idler 20. This idler 20 is located a greater distance away from the flexing roll 4 than is the idler 9. The direction of travel of the belts is indicated by arrows. From the idler 20 the belts 8 pass over an 70 idler 21 and thence over the idlers 11 and 19 to an idler 13^a which is mounted similarly and serves the same function as the idlers 13.

The belts which cooperate with the belts 7 and 8 to grip the packs are numbered 22 and 75 23 respectively. Considering first a belt 22, it passes over an idler 24, thence around the flexing roll 4. It is not in direct contact with the flexing roll 4, but lies over the belt 7. The belt 22 extends around an idler 25 80 and thence around a tension idler 13^b, and idlers 26 and 27 to the idler 24. Each belt 23 passes around the idler 24, thence around the flexing roll 4. The belts 23 are not in direct contact with the flexing roll, but lie over the 85 belts 8. The belts 23 extend around an idler 28, thence around tension idlers 13^c, thence over the idler 27 to the idler 24.

When a pack is fed between the belts, it is gripped and carried around the flexing roll 90 4. This results in flexing the pack along successive lines of flexure, which lines extend all the way across the pack. Stated in another way, the pack is flexed over its entire width, and the line of flexure is progressively 95 moved across the pack. The pack is preferably fed corner first so that the lines of flexure run diagonally.

The provision of independent tension idlers for the separate belts is of advantage because 100 it lets the belts yield in different amounts, as is required. With the arrangement of belts and idlers as shown, there is no danger of the belts tending to creep over one another. They are free to move at the required velocity and thus undue wear is prevented.

In order to ensure separation of the pack at the rear end, it is important that the leading portion be tightly gripped while the rear end is passing around the flexing roll. In 110 order to do this, I impart to the sheet a flexing action similar in all respects to

the first, but in the reverse direction. It is for this purpose that the flexing roll 3 is provided. The packs are fed to the flexing roll 3 by belts 29 and 30, engaging one side of the pack, and belts 31 and 32, engaging the other side. The belts 29 and 30 lie below the belts 22 and 23, and are of substantially the same width as those belts. The belts 31 and 32 lie below the belts 7 and 8 and are of substantially the same width. The belts 29 and 30 engage the flexing roll 3 while the working portions of the belts 31 and 32 lie over the belts 29 and 30.

The path of each belt 29 is as follows: From the flexing roll 3 over an idler 33 to an idler 34, thence to a tension idler 13¹, thence over idlers 35 and 36 back to the flexing roll 3. The path of each belt 30 is as follows: From the flexing roll 3 over the idler 33 to an idler 37, thence over a tension idler 13² back to the idler 37, thence over an idler 38 and the idler 25 to the flexing roll 3.

The path of each belt 32 is as follows:— from the flexing roll 3 over the idler 33, thence to a tension idler 13¹ to an idler 39, thence over idlers 40 and 41 to the flexing roll 3. The path of each belt 31 is as follows: from the flexing roll 3 over the idler 33, thence to a tension idler 13², thence over an idler 42 around the idlers 39 and 40 to the idlers 20, and thence to the flexing roll 3. It will be seen from the above description that the working portions of the several belts in the plane through which a pack travels between the flexing roll 4 and the flexing roll 3 may be said to be "overlapping", that is to say, before those belts which carry the pack around the flexing roll 4 have entirely released any portion of the pack, a part of that same portion is engaged by certain of the belts which carry the pack around the flexing roll 3. This is due to the fact that common idlers are employed for belts in each set. Considering, for example, the idler 20, it will be seen that a belt 8 travels over the idler 20 before it is directed upwardly to the idler 21, while the belt 31 travels around the opposite side of the idler, adjacent to the belt 8, on its way to the flexing roll 3. This means that portions of the belts 8 and 31 will lie side by side and simultaneously engage the pack. Similarly, portions of the belts 22 and 30 lie side by side and simultaneously engage the pack. It will also be noted that the belts 8 extend past the idler 25 so that the belts 8 and 30 engage the pack at the same time, but on opposite sides thereof.

As above pointed out, it is desired to feed the packs corner first. The individual tension idlers for the belts hold the belts tight at all times, and the arrangement of idlers is such as to prevent creeping of one belt upon another.

If desired, the gear 6, which is connected to the shaft of the flexing roll 4, may be made

slightly larger than the corresponding gear on the shaft of the flexing roll 3. This will make the flexing roll 4 rotate a little more slowly than the flexing roll 3. As a result, the belts which cooperate with the flexing roll 3 will tend to pull the pack forward faster than it is normally moved by the belts cooperating with the flexing roll 4, thus putting the sheets under tension and eliminating any danger of buckling the pack.

The separated sheets are discharged onto a guide 43.

In operation the belts grip the pack, and as it is forced around a flexing roll, the sheets tend to slide on one another just as the pages of a magazine slide over one another when it is rolled parallel to the binding. The continued sliding of the sheets over one another causes them to separate despite the sticking between surfaces of adjacent sheets and despite the interlocking edges occasioned by shearing. The idlers 27 and 40 serve to engage the outside belts when a pack is passed through the machine and, acting through such belts, are effective for causing initial deflection of the leading edge of the pack. The distance between the idlers 27 and 40 and the outside belts lying over adjacent flexing rolls is preferably about the thickness of a pack. These rolls are made adjustable toward or away from the flexing roll, and also adjustable to different positions therearound.

As will be seen from the drawings, and particularly Figure 1 thereof, the belts are so arranged that when they pass around the flexing rolls they are spaced apart a distance less than the width of each belt. This is found in practice to be highly advantageous, particularly if the packs are fed cornerwise, because it insures that gripping of the pack will be obtained sufficiently close to the leading and trailing corners to properly guide them and cause separation of the sheets at these corners. It is also of advantage if the packs are fed squarely to the machine because a very large percentage of the surface area of the pack is gripped, thus expediting sheet separation.

The term "belts" is used herein as a word of general definition, and not of limitation, and is intended to include equivalent devices such as chains, chain belts and the like. The term "pack" is employed to cover a number of adherent sheets whether produced by pack rolling or not.

I have illustrated and described the present preferred form of my invention, but it will be understood that it may be otherwise embodied or practiced within the scope of the following claims.

I claim:—

1. The method of separating packs, which comprises flexing the pack through substantially a half circle, causing the zone of flexure to move progressively along the pack, such

- flexing extending substantially the width of the pack, the lines of flexure lying diagonally of the pack.
2. Apparatus for separating packs, comprising cooperating belts adapted to receive material therebetween, guide means causing the belts to travel in a curved path, and yieldable tension means for the belts.
3. Apparatus for separating packs, comprising a plurality of flexing rolls, and a plurality of cooperating pack gripping belts for the same side of the pack associated with each flexing roll and adapted to carry packs therearound, the belts in different sets lying in overlapping relationship.
4. Apparatus for separating packs, comprising a flexing roll, a plurality of belts lying over the flexing roll, and a second set of belts, each lying over those portions of the first mentioned belts which are in engagement with the flexing roll.
5. Apparatus for separating packs, comprising a flexing roll, a plurality of belts lying over the flexing roll, a second set of belts, each lying over those portions of the first mentioned belts which are in engagement with the flexing roll, and separate yieldable tension means for the several belts.
6. Apparatus for separating packs, comprising a plurality of flexing rolls, cooperating belts adapted to cause packs to travel around such rolls successively, and means for driving one flexing roll at a lower speed than a succeeding flexing roll.
7. Apparatus for separating packs, comprising a flexing roll, a plurality of cooperating material gripping belts travelling thereover and separate yieldable tension means for the belts.
8. Apparatus for separating packs comprising cooperating belts adapted to receive material therebetween, guide means causing the belts to travel in a curved path, and separate yieldable tension means for the several belts.
9. Apparatus for separating packs comprising a plurality of flexing rolls, a belt extending around one flexing roll so as to flex material between the belt and the roll in one direction, and a second belt extending around another flexing roll and adapted to guide the material between the last mentioned belt and said second flexing roll so as to flex the material in the opposite direction.
10. Apparatus for separating packs, comprising a plurality of flexing rolls, and a plurality of belts for each flexing roll adapted to grip a pack and guide it around their flexing roll, the belts for one flexing roll being arranged to deliver the pack to the belts of a succeeding flexing roll.
11. Apparatus for separating packs, comprising a plurality of flexing rolls, and a plurality of belts for each flexing roll adapted to grip a pack and guide it around their flexing roll, the belts for one flexing roll being arranged to deliver the pack to the belts of a succeeding flexing roll.
12. Apparatus for separating packs, comprising a plurality of flexing rolls, a plurality of belts for each flexing roll adapted to grip a pack and guide it around their flexing roll, the belts for one flexing roll being arranged to deliver the pack to the belts of a succeeding flexing roll, and separate yieldable tensioning means for the several belts.
13. Apparatus for separating packs, comprising a plurality of flexing rolls, and a plurality of cooperating pack gripping belts for each side of the pack associated with each flexing roll and adapted to grip packs fed between them and carry them around the flexing roll, the belts for one flexing roll being arranged to feed the pack to the belts for a succeeding flexing roll.
14. Apparatus for separating packs, comprising a plurality of flexing rolls, and a plurality of cooperating pack gripping belts for each side of the pack associated with each flexing roll and adapted to grip packs fed between them and carry them around the flexing roll, the belts for one flexing roll being arranged to feed the pack to the belts for a succeeding flexing roll, portions of the belts for one flexing roll lying alongside portions of the belts for the succeeding flexing rolls.
15. Apparatus for separating packs, comprising a flexing roll, a belt adapted to engage a face of the pack and flex it around the flexing roll, and deflecting means lying outside the belt for engaging the same and acting through the belt to guide the pack around the flexing roll.
16. Apparatus for separating packs, comprising a flexing roll, a belt adapted to engage a face of the pack and flex it around the flexing roll, and means lying outside the belt for engaging the same and effective for causing initial deflection of the leading edge of the pack.
17. Apparatus for separating packs, comprising a flexing roll, a belt adapted to engage a face of the pack and flex it around the flexing roll, and means lying outside the belt and spaced therefrom a distance substantially equal to the thickness of a pack and effective for engaging the belt and acting through it to deflect the pack.
18. Apparatus for separating packs comprising a plurality of flexing rolls, cooperating belts adapted to cause packs to travel around such rolls successively, at least some of the belts associated with one of the flexing rolls being so arranged that they cooperate

with one of the flexing rolls but not with another of such flexing rolls, and means for driving one flexing roll at a lower speed than a succeeding flexing roll.

5. 19. Apparatus for separating packs comprising a flexing roll and a plurality of belts adapted to engage a face of the pack and flex it around the flexing roll, the belts being so arranged that those portions which 10 are actively engaged in flexing the pack are separated a distance less than the width of a belt.

20. 20. Apparatus for separating packs com-

prising a flexing roll and a plurality of belts arranged in sets, belts in one set moving in 15 a path other than belts in another set, but the belts in the several sets being arranged to lie side by side as they pass around the flexing roll, the belts being effective for guiding the pack around the flexing roll, the portions 20 of the belts lying adjacent the flexing roll being spaced apart a distance less than the width of a belt.

In testimony whereof I have hereunto set my hand.

CHARLES B. MORAN.
